(57) **CLAIM**

The ornamental design for a tip for laser handpiece, as shown and described.

DESCRIPTION

FIG. 1 is a perspective view of the tip for laser handpiece; FIG. 2 is a front view of the tip for laser handpiece shown in FIG. 1;

FIG. 3 is a rear view of the tip for laser handpiece shown in FIG. 1;

FIG. 4 is a left view of the tip for laser handpiece shown in FIG. 1;

FIG. 5 is a right view of the tip for laser handpiece shown in FIG. 1;

FIG. 6 is a top view of the tip for laser handpiece shown in FIG. 1; and,

FIG. 7 is a bottom view of the tip for laser handpiece shown in FIG. 1.

In the drawings, the broken lines depict environmental subject matter only and form no part of the claimed design.
